(57) **CLAIM**

The ornamental design for an introducer needle assembly, as shown and described.

DESCRIPTION

FIG. 1 is a perspective view of an introducer needle assembly showing my design;

FIG. 2 is a rear perspective view of the assembly of FIG. 1; FIG. 3 is a front elevational view of the assembly of FIG. 1; FIG. 4 is a rear elevational view of the assembly of FIG. 1; FIG. 5 is a top plan view of the assembly of FIG. 1; FIG. 6 is a right-side elevational view of the assembly of FIG. 1; and,

FIG. 7 is a bottom plan view of the assembly of FIG. 1. The broken lines shown in FIGS. 1, 2, 3 and 5 through 7 are for illustrative purposes only and form no part of the claimed design.
